UNITED STATES PATENT OFFICE.

JOHN H. VOGELSANG, OF COVINGTON, KENTUCKY.

THROATLESS HORSE-COLLAR WITH COMBINATION-PLATE.

SPECIFICATION forming part of Letters Patent No. 767,371, dated August 9, 1904.

Application filed September 6, 1902. Renewed April 8, 1904. Serial No. 202,249. (No model.)

To all whom it may concern:

Be it known that I, JOHN H. VOGELSANG, a citizen of the United States, and a resident of the city of Covington, in the county of Kenton and State of Kentucky, have invented certain new, valuable, and useful Improvements in Throatless Horse-Collars with Combination-Plates, of which the following is a specification.

10 One object of my invention is to provide improved devices which shall take the place of those heretofore used at the throat of the collar.

15 Another object of my invention is to prevent the rim from tearing away from the body of the collar.

Another object is to render the collar unbreakable at the center of its throat.

20 Another object is to prevent the collar from bending at the center of its throat.

By the attainment of any one of these objects I prevent the horse from getting choked by the undue bending or collapse of the collar.

25 Other objects of my invention will be hereinafter apparent.

The several features of my invention and the various advantages resulting from their use, conjointly or otherwise, will be apparent from the following description and claims.

30 In the accompanying drawings, making a part of this application, and in which similar letters of reference indicate corresponding parts, Figure 1 is a perspective view of the front of a horse-collar embodying my invention.

35 In this figure the rim or front wale of the collar is toward the spectator, and in this view essentially all of the under side of the bottom of the collar is seen. Fig. 2 represents in perspective the rear side of the collar.

40 In this figure the after wale or body of the collar is toward the spectator. Fig. 3 represents a vertical transverse section from front to rear of the collar at the throat portion of the latter. This section is taken in

45 the plane of the dotted line 3 3 of Fig. 2. Fig. 4 is a view of the under and front side of my new under or front throat-plate. Fig. 5 is a view of the upper and rear side of my new upper or rear throat-plate.

I will now proceed to describe my invention 50 in detail.

The collar, exclusive of my improved attachments, is constructed as follows: There is a body portion A at the rear, and this is known in the art as the "after wale," "body side," or 55 "pad." This portion when in use lies behind the hames. There is a rim B, known as the "fore wale" or "small roll," which is for the greater portion of its extent of a diameter less than the thickness of the body side A. The rim B 60 is united to the body side A in the usual manner. This body side A and the rim B are preferably divided at the top in the usual manner to allow the collar to be fitted to horse-necks of various sizes. The usual collar-strap C, attached to one half of the collar, and the usual buckle attached to the other half of the collar, the strap being made to engage the buckle, are present, and the usual lining (upper pad) M within the upper part 70 of the collar to prevent the upper ends of the collar, secured together by the strap and buckle, from abrading the upper part of neck of the horse is also present at the top of the collar, a part of the strap C being shown. 75

In the collar constructed for the application of my invention the stuffed body side A does not continue on either side of the collar down to the middle of the throat, but, on the contrary, stops at the curved line A² A² at the 80 front and at the correspondingly-curved line B² B² at the rear; but the leathers continue to the middle of the throat and form a connecting portion F between the lower ends of the stuffed portions or pads A² A² of the body 85 A. This connecting portion is at the throat of the collar and extends forward from the throat portion of the roll or rim B up to a plane in line with the front edge of the joint or welt G. The leathers of the front and 90 back sides of the body of the collar are usually lapped and properly secured together at a median line at the center of this throat. The juncture is usually made by stitching. Thus in the bottom and front of the throat between 95 the body sides or pads A A there is now present a depression (indicated by the curved line A³ and the opposite curved line A³ and

located between said lines) and which I denote W. In the top and rear of the throat there is now present a depression (indicated by the curved line B² and the opposite curved line B³ and located between said lines) and which I denote X. It is in the lower and front spaces W thus formed that I locate my improved metal throat-piece G, and it is in the upper and rear space X thus formed that I locate my improved metal throat-piece H; but each of these metal throat-pieces G and H not only occupy their respective spaces W and X, but they also extend out and over and against the joint or welt piece G².

15 My improved throat-piece G is curved substantially as shown and bends over and down at the rear for a short distance, making a curved extension G². So, also, this improved throat-piece G at the front curves forward. 20 Such curve G² fits the groove between the roll B and the said body portion F. The throat-piece H at the rear curves over and down in a curved extension H², similar to the curved extension G² of the throat-piece G. Between 25 these pieces G and H lies the portion F of the collar. This portion F being flexible conforms to the shape of these pieces G and H. Hence my metallic throat-pieces and the portion F will be as one. These parts G, F, and 30 H are duly riveted together. The curved extensions G² and H² deprive the rear and inside of any sharp abutments, edges, or corners and also by their tubular shape increase the strength of the plates and of the entire structure at the throat. The absence of pad-stuffing at the throat secures elegance of form and 35 lightness of appearance.

The combination of the metallic curved throat-pieces extending at each end in narrow rows G¹ G² H¹ H² to the right and left up the side portions of the collar imparts 40 great strength and stiffness to the collar at and in the vicinity of the throat of the collar. All breaking of the collar at this locality and 45 thus injury to it and injury to the horse are avoided. The collar is very durable. The throat portion being thus thin and without stuffing is well adapted to receive the slot K, which is present in and through the throat- 50 plates G and H, as well as in and through the leather portion F. Through this slot is passed the choke-strap. The pole-strap when in use embraces the throat of the collar, and my invention prevents the pole-strap from cutting 55 the collar and wearing it in two. My invention also affords great ventilation for the col-

lar at the throat-piece, as it keeps the throat-piece off from the neck and allows air to circulate between the throat-piece and the horse. 60 This is an important advantage.

The extensions G¹ G² H¹ H² may, if desired, be longer and run up farther on the welt.

The elasticity of the collar is in no wise impaired. On the contrary, the collar can be sprung apart as needed at the top or lower 65 down.

Other obvious advantages result from my invention, among which may be mentioned that it is simple of construction and economical of cost and a combination readily attained. 70

The parts G¹ and H¹ are, in effect, laterally-extending arms on the reinforcing-pieces, and said pieces have also upwardly-extending portions or arms G² H².

What I claim as new and of my invention, 75 and desire to secure by Letters Patent, is—

1. In combination in a horse-collar, a rim B, a stuffed body portion A having its padded sides ending short of the medial line of the throat and having leathers extending and forming a depressed continuation of the said 80 padded portions, and a reinforcing-piece secured to the said leather extensions at the throat, said reinforcing-piece having an upward and two laterally-extending portions or 85 arms and being curved from its upper to its lower edge, said laterally-extending arms lying along the lower edge of the collar while the padded portions lie along the upper edges of the said laterally-extending arms and up 90 to the upwardly-extending arm, substantially as described.

2. In combination in a horse-collar having its two side pads A with leathers extending across the space between them at the throat 95 forming a depression on the outside and inside, a reinforcing-piece for the outside and a reinforcing-piece for the inside, each of which is provided with an upwardly and with two laterally extending portions or arms located 100 in the depression and riveted to the leather extensions, said laterally-extending arms lying along the lower edge of the collar while the padded portions lie along the upper edges of the said laterally-extending arms and up to 105 the upwardly-extending arm, substantially as described.

JOHN H. VOGELSANG.
